UNITED STATES PATENT OFFICE

CHRISTEN CHRISTENSEN, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS

SWITCH LOCK

Application filed June 7, 1923. Serial No. 643,833.

The present invention relates to switch locks, having particular reference to locks for disconnecting switches, such as are used in power transmission systems. The lock of my invention is suitable for both outdoor and indoor use.

The fundamental object of the invention is to improve the lock mechanism for switches of this class by reducing the number of operating parts; and by removing certain of these parts from between the switch blades and disposing them outside of the blades, whereby larger parts may be employed and a more rugged and serviceable construction obtained.

A further object is to provide means for weatherproofing lock mechanism of this character.

Referring to the accompanying drawings illustrating a preferred embodiment of my invention:

Figure 1 illustrates in side elevation an exemplary form of vertical switch with my improved locking mechanism embodied therein;

Figure 2 is a front or edge view of the same;

Figure 3 is an enlarged sectional view taken approximately on the plane of line 3—3 of Figure 2;

Figure 4 is a transverse sectional view taken on the plane of line 4—4 of Figure 3;

Figure 5 is a longitudinal sectional view taken on the plane of line 5—5 of Figure 3;

Figure 6 is a transverse sectional view taken on the plane of line 6—6 of Figure 3;

Figure 7 is an isolated perspective view of the latch or locking bolt;

Figure 8 is a fragmentary sectional view of a modification;

Figure 9 is a medial sectional view of a different form of lock releasing member;

Figure 10 is a fragmentary view, similar to Fig. 3, illustrating another modified construction;

Figure 11 is a bottom plan view of the lock releasing member employed in Figure 10, and

Fig. 12 is a fragmentary elevational view

showing the lock releasing member provided with two eyes.

Referring to Figure 1, the switch 11 is pivoted at its lower end on a pivot bolt 12 passing through a pivot terminal 13 supported on the insulator 15. The upper end of the switch 11 engages with a contact terminal 16, which is supported on an insulator 17. The two insulators 15 and 17 are mounted in any suitable manner upon a mounting base 18 which is adapted to be secured to the pole-top or tower.

The switch 11 is built up of two spaced blades 19—19 which engage over opposite sides of the terminals 13 and 16. Spring washers 21 engage under the heads of the pivot bolt 12 and produce a light pressure contact between the blades 19—19 and the terminal 13. A bolt 22 passes through the two blades 19 immediately below the upper contact terminal 16, and has similar spring washers 23 for obtaining a resilient pressure between these blades and the sides of the terminal 16.

The upper contact terminal 16 is formed with a locking hook or shoulder 24 in its upper edge having an inclined front face for camming the locking bolt up over the top of the hook 24. The locking bolt or latch is indicated at 25 and is disposed for reciprocating motion between the upper free ends of the switch blades 19. This locking bolt is clearly shown in Figures 3 and 7, and is of T-shaped outline having overhanging arms 25' projecting beyond the lateral edges of the switch blades 19. This locking bolt is guided for reciprocating motion between the switch blades by a pair of transverse bolts 26 engaging on each side of the locking bolt, and by a pivot bolt 27 which passes through the switch blade and engages in a slot 28 in the T end of the locking bolt. Additional guiding support is offered by a pin 29 which is disposed in a slot 31 in bolt 25, and which serves as a stationary abutment for a compression spring 32 confined between the pin 29 and the other end of the slot 31. The ends of the pin 29 are reduced at 29' for engaging in reduced apertures in the switch blades, the enlarged portion of the pin serving as a

spacer between the switch blades to prevent the switch blades from binding the action of the locking bolt 25. The two transverse bolts 26 are provided with spring washers 33 under 5 the bolt heads on each side of the switch to urge the switch blades into close contacting relation with the contact terminal 16. This terminal 16 may be made somewhat thicker than the locking bolt 25 so that the pressure 10 of the spring washers 33 is effective for maintaining close contact with the terminal 16 without cramping the motion of the locking bolt.

The lock releasing member is broadly designated 34, and comprises an open rectangular portion 35 and two spaced arms 36 extending therefrom to an eye or ring 37 for receiving the hook on the end of the actuating pole. The lock releasing member 34 is pivotally supported on the ends of the switch blades 19 by extending the pivot bolt 27 through the sides of the open rectangular portion 35. The ends of the frame portion 35 abut the over-hanging shoulders 25' of the locking bolt, as indicated at 38, the pressure of the spring 32 drawing the shoulders of the locking bolt down against the forward edges 38 of the locking member.

The arms 36 of the lock releasing member 34 project diagonally so as to dispose the eye or ring 37 above and to one side of the plane of the switch 11, as clearly shown in Figure 1; or, instead of the diagonal arms 36, an arcuate web may be formed on the rectangular portion 35 for receiving a plurality of eyes 37', one on each side of the switch blade and perhaps one in the center. The switch is opened by inserting the hook on the end of the switch operating pole into the eye 37 and pulling downwardly. This rocks the lock releasing member 34 around the bolt 27 as a pivot and thrusts one shoulder 38 up against the locking bolt shoulder 25', thereby retracting the locking bolt from engagement with the hook 40 stop 24 against the pressure of the spring 32. Thereafter the continued downward pull on the switch operating pole is operative to pull the switch 11 off of the contact terminal 16 and to a downward, open position. In the 45 reclosing of the switch the hook on the end of the operating hole may be reinserted into the eye 37 and the switch swung upward into locking engagement with the contact terminal 16 in an obvious manner, or the hook on the 50 end of the operating pole may be merely engaged with the under side of the switch blade and the latter pushed up into locking engagement over the contact terminal 16.

The outer ends of the switch blades 19—19 55 are rounded to permit the forward edges of the shoulders 38 to revolve around the ends of the blades, and the rear inner edges of the frame portion 35 are chamfered back at 40 to prevent striking against the edges of the 60 blades upon the initial turning of the lock

releasing member 34. It is however to be noted that the chamfered edges 40 engage the respective sides of the blade, upon the continued turning of the release member 34, thereby limiting the extent of movement of the release member with respect to the blades. This prevents the stressing of the bolt 25 and the bolt 27, which would otherwise be brought into engagement with one another. At this time the member 25 is out of engagement with the shoulder 24 and further pulling upon the release member causes it to move as a unit with the switch blade about the pivot bolt 12. The two transverse bolts 26 with their spring washers 33 hold the blades in intimate contact with the contact terminal 16 but do not permit the width of the terminal to spread the ends of the blades against the inner sides of the lock releasing portion 34 and thereby bind the lock releasing portion.

Also the nuts on the pivot bolt 27 may be tightened against the adjacent portions of the releasing member without affecting the floating characteristic of the switch blades. That is to say, the nuts on the pivot bolt 27 will not constrain the outward movement of the switch blades associated therewith. The inner walls of the frame portion 35 will serve in a measure as a means for limiting the outward movement of the floating blades. Thus it will be seen that since the frame 35 is rigid no matter how tight the nuts on the pivot bolt 27 are tightened the blades will never be pressed towards each other by the releasing member 34. The releasing member, however, is adapted to cooperate with the bolts 26 in limiting the outward displacement of the blades that is to say should the bolts become loosened the frame portion 35 of the releasing member 34 will serve to limit the outward displacement of the blades. From this it will be also evident that by tightening the aforesaid nuts the locking bolt intermediate the blades will not be locked or bound against operation on account of the rigidity of the frame 35.

It will be observed from Figure 3 that the lock releasing member 34 is universal in that it can be mounted on the end of the switch blade to face in either direction. The use of two releasing shoulders 38 and two overhanging shoulders 25' on the locking bolt permit of this reversal of the lock releasing member, and of its operation by a push or a pull from either side of the switch blade. This universally adapts the present switch to a mounting in either a vertical, horizontal or inclined position and at any point relative to the direction of reach of the switch operating pole; the ability to reverse or invert the lock releasing member 34, enabling a standard design of switch to be employed in any of these situations without any change of parts or construction.

In lieu of a diagonal extension of the op. 130

erating eye 37, the eye may be extended directly out from the lock releasing member 34 in prolongation of the switch blade, as shown in Figure 8. Another modification is to form the lock releasing member with a relatively wide fin or web 30 in which are provided two eyes 37'. This modification is of particular advantage with double throw switches, as with such arrangement one of the eyes is always accessible whether the switch blade is up or down.

In Figure 9 I have illustrated a slightly modified form of lock releasing member 34. In this form the lock releasing member is constructed as a substantially closed casing, or at least closed on the top for housing the end of the switch blade and the lock releasing mechanism. The member 34 is constructed of two side walls 41 closed over on the top and side by a transverse wall 43. The eye 37 is formed by aligned apertures in the two side walls 41. The overhanging shoulder 25' of the locking bolt projects out beyond the sides of the switch blade, as in the preceding embodiment, and co-operating with these shoulders are any suitable projections 38' carried by the member 34, such as pins or screws extending through the two side walls 41. By virtue of its enclosed form, the lock releasing member 34 functions as a hood for protecting the upper end of the switch blade and the locking mechanism from sleet, rain, etc.

This practice of employing the lock releasing member as a weatherproofing member for protecting the lock mechanism has further illustration in Figs. 10 and 11. Here the lock releasing member 34' is constructed as a closed, flat-sided member of bowl shaped contour which completely surrounds the top and sides of the switch blades and locking bolt and prevents the entrance of the weather down into the top of the lock mechanism. As shown in Fig. 11, the side walls of the interior chamber 45 are formed with inwardly extending hubs 46 against which bear the switch blades and through which passes the pivot bolt 27. Two tongues or lugs 47 project inwardly from the ends of the enclosing member for disposal between the switch blades where they are adapted to engage the shoulders 25' of the locking bolt. In this instance the shoulders 25' do not extend beyond the edges of the switch blades. Either arrangement may be employed, it being noted that in each case the lugs 47 and shoulders 25' may be made as thick as the space between the blades, which insures sufficient strength and the proper freedom of operation. The diagonal arm 36' carrying the eye 37' is formed with a cored passage 48 co-extensive with the chamber or opening 45 in the main body part. This passage has an outlet port 49 opening into the interior of the eye 37 along the side wall thereof. By

reason of this arrangement of passage 48 and port 49, when the switch blade is swung downwardly the chamber 45 will not trap the rain and sleet dripping into the same from the switch blades, but will vent this accumulation out through the passage 48 and port 49. When the blades are upright the protecting enclosure of the eye 37' prevents the entrance of rain into the port 49. This form of lock releasing member may, of course, be reversed similarly to the preceding form.

The practice of using substantially the entire space between the free ends of the switch blades for the locking bolt, and pivoting the lock releasing member outside of the switch blades, as shown in each of the preceding embodiments, has the advantages of permitting the use of larger and stronger parts, a simple and inexpensive construction and assembly, and a smoothly working operation.

I claim:

1. In combination, a pair of switch terminals, a switch blade for connecting said terminals, said blade comprising a pair of spaced floating blade members a T-shaped locking bolt carried between said switch blade members, the ends of the T-arms projecting beyond the edges of said blade members, and a lock releasing member pivotally carried on said blade and positioned outside the space between said blade members and engageable with said locking bolt projections outside the areas of the blade members and beyond the edges thereof.

2. In combination, a pair of switch terminals, a switch blade for connecting said terminals, a locking member carried by said switch blade, a lock releasing member forming a protecting enclosure over said locking member, said lock releasing member comprising an eye, and a drain passage between the interior of said lock releasing member and said eye.

3. In combination, a pair of switch terminals, a switch blade for connecting said terminals, a locking member carried by said switch blade, a lock releasing member forming a protecting enclosure over said locking member, a passage for draining said lock releasing member when said switch blade is down, and means for minimizing the entrance of the foreign matter such as rain and sleet into said passage when said switch blade is up.

4. In combination, a pair of switch terminals, a pair of floating blades for connecting said switch terminals, means for retaining said floating blades against the sides of said switch terminals, a locking member disposed between the free ends of the switch blades, and a lock releasing member having an operating arm terminating in an eye and socket mounted on the exterior sides of the free ends of the switch blades, said socket being adapted to embrace a portion of said locking

member, said locking member having laterally projecting shoulders, and said socket having shoulders co-operable with the shoulders of the locking member beyond the width of the blades.

5. In an electric switch, a pair of connected parallel blade members movable in unison, a locking lath nested between the blade members intermediate the ends thereof, said lath having a portion projecting beyond the edges of the blade members, and a latch releasing member carried by the blade members outside of the space between the blade members, and embracing the end of the blade members, said releasing member cooperating with said projecting portion of the latch to control the latch.

6. In an electric switch, a pair of connected parallel blade members movable in unison, a terminal, the opposite sides of which are engaged by the respective blade members, a latch nested between the blade members intermediate the ends thereof, locking means on the terminal cooperating with the latch for locking the blades to the terminal member, said latch having a portion projecting beyond the edges of the blade members, and a latch releasing member carried by the blade members outside of the space between the blade members and embracing the end of the blade members, said releasing member cooperating with said projecting portion of the latch to control the latch.

7. In an electric switch, a pair of switch terminals, a pair of parallel switch blades for connecting said terminals, locking means mounted between said blades for locking the blades with respect to said terminals, and a movable lock releasing member carried by and extending around both outer sides of the pair of switch blades and having an aperture therein engageable by a switch operating hook, said releasing member having a limited movement to each side of an intermediate normal position, and said lock being actuated alike by the movement in either direction from the intermediate position.

8. In an electric switch, a terminal, a pair of connected parallel blade members movable in unison into and out of engagement with the opposite sides of the terminal, a latch nested between the blade members intermediate the ends thereof for locking the members with respect to said terminal, and a latch releasing member carried by the blade members outside of the space between the blade members and forming a covering protecting hood for the ends of said blade members and the latch, said releasing member controlling the release of the latch.

9. In a switch, a pair of blades adapted to embrace a contact between them, a reciprocating locking latch mounted between the blades for locking the blades against movement away from the contact, and a pivoted

lock releasing member on the outside of the blades for controlling said locking latch, said lock releasing member encasing the end of the blades and forming a sleet hood therefor.

In witness whereof, I hereunto subscribe my name this 24th day of May, 1923.

CHRISTEN CHRISTENSEN.
